CLAIM

The ornamental design for a remote controller for a computer or an MP3 player device, as shown and described.

DESCRIPTION

FIG. 1 is a perspective view of a remote controller for a computer or an MP3 player device showing my new design as seen from one angle;

FIG. 2 is top view thereof;

FIG. 3 is a side elevational view thereof as seen from the left in FIG. 2;

FIG. 4 is a bottom view thereof;

FIG. 5 is a side elevational view thereof as seen from the right in FIG. 2;

FIG. 6 is a front elevational view thereof;

FIG. 7 is a back elevational view thereof; and,

FIG. 8 is a perspective view thereof as seen from an alternative angle.
